UNITED STATES PATENT OFFICE.

FREDERICK M. THOMSON, OF ATLANTA, GEORGIA.

DETACHABLE SHOE-HEEL.

1,215,080.

Specification of Letters Patent. Patented Feb. 6, 1917.

Application filed September 5, 1912. Serial No. 718,694.

To all whom it may concern:

Be it known that I, FREDERICK M. THOMSON, a citizen of the United States, residing at Atlanta, in the county of Fulton and 5 State of Georgia, have invented certain new and useful Improvements in Detachable Shoe-Heels, of which the following is a specification.

The invention relates to shoes and has for 10 its object the provision of means by which the wear portion of the heel is detachably secured to the shoe upper to permit of the removal of the shoe heel whenever desired for the purpose of changing the wear portion 15 of the heel in the case of persons having the habit of wearing one side of the heel more than the other, so that the heels may be transposed or to permit of having the heels made of leather and other heels made 20 of rubber that may be interchanged when desired.

The invention consists of a plate adapted 25 to be secured to the body of the shoe and provided with a recess having inwardly inclined edges and a shoulder adjacent to the outer edge of the plate and another plate 30 adapted to be secured to the removable portion of the heel having its edges beveled to engage the inclined portions of the edges 35 of the recess in the mating plate and having an offset portion formed thereon adapted to engage the shoulder on the first-mentioned plate to hold the heel from accidental displacement.

35 My invention will be described in detail hereinafter and illustrated in the accompanying drawings, in which,

Figure 1 is a longitudinal sectional view 40 of a shoe showing my improved heel fastener in position thereon;

Fig. 2, a view in perspective of the plate adapted to be secured to the body of the shoe;

Fig. 3, a similar view of the plate adapted 45 to be secured to the shoe heel; and

Fig. 4, a longitudinal sectional view of the plate shown in Fig. 2.

In the drawings similar reference characters will be used to designate correspond- 50 ing parts throughout the several views.

A indicates a shoe having a piece of leather or other similar material 1 forming the base of the heel, said piece of leather 1 being provided with a recessed portion 2 55 in which is secured a plate 3. The plate 3 is shorter than the length of the heel and

narrower than the width thereof so that when the plate is in position, it is hidden by the sides and rear portion of the piece of leather 1. The plate 2 is secured to the piece of leather 1 by means of screws or other suitable fastenings secured to the openings 4 therein. The under side of the plate 3 is provided with a recess having its walls formed inwardly beveled as shown 60 at 5 and the plate 3 is also provided with a socket 6 having a vertical shoulder 6^a and an inclined face 6^b.

The wear portion of the heel 7 has secured thereto a plate 8 by means of screws 70 or other suitable fastenings inserted through openings 9 therein and is provided with an integral tongue 10 having an offset portion forming a projection 11 that is adapted to engage the shoulder 6^a of socket 6 when the 75 wear portion 7 of the heel is in position as shown in Fig. 1. 12 indicates a lug or projection on the free terminal of the tongue 10 that is adapted to be engaged by the finger or thumb to spring the tongue down- 80 wardly so that the projection 11 is out of engagement with the slot 6 when it is desired to remove the wear portion 7 of the heel. The upper surface of the wear portion 85 of the heel is formed with a recess 13 to permit downward movement of said tongue 10. The side edges of the plate 8 are beveled as shown at 13 to engage the beveled portions 5 of the walls of the recess 4 in the plate 3. 90

In use it will be apparent that when it is desired to remove the wear portion 7 of the heel from the body of the shoe the spring tongue 10 is flexed downwardly by grasping the lug 12 on the end thereof and the wear portion 7 is moved forwardly so that the plate 8 is moved from engagement with the recess in the plate 3. In replacing the wear portion 7 in position, it will be apparent that it is only necessary to insert the 100 end of the plate 8 in the recess and move the wear portion 7 in a rearward direction. When plate 8 reaches the end of the recess, the offset portion 11, by engaging the shoulder 6^a of socket 6 in the plate 3 will hold 105 said plate 8 and the wear portion 7 from accidental displacement.

Having thus described my invention what I claim is:—

The herein-described detachable heel in- 110 cluding a permanent relatively thick lift carried by the shoe and provided in its

lower face with a substantially oblong recess extending rearwardly from the front edge of the said lift and terminating short of the rear edge thereof, a detachable heel section, a fixed substantially oblong metallic plate secured to the relatively thick lift and contained wholly within the said recess and arranged in flush relation with the lower face of the said lift, said plate being provided in its lower face with a recess extending inwardly from the front edge of the plate and having inwardly beveled side walls and provided adjacent to its front end with a transverse shoulder extending entirely across the recess and formed by a thickened portion of the said plate, and a removable plate secured to the upper face of the detachable section of the heel and fit-

ting in the recess of the fixed plate and having beveled side edges to slidably interlock with the said side walls of the recess and split longitudinally near its side edges to provide a relatively wide spring tongue, the latter being angularly bent to form an upper shoulder to engage the shoulder of the said recess, said tongue being also provided at its front end with an integral finger of less width than the tongue and extending upwardly at the front edge of the fixed plate.

In testimony whereof I affix my signature in presence of two witnesses.

FRED M. THOMSON.
